WILLIAM R. LAKEY, OF DENTON, TEXAS.

MILLING-MACHINE.

1,085,921.

Specification of Letters Patent.

Patented Feb. 3, 1914.

Application filed July 23, 1912. Serial No. 711,145.

To all whom it may concern:

Be it known that I, WILLIAM R. LAKEY, a citizen of the United States, residing at Denton, in the county of Denton and State 5 of Texas, have invented a new and useful Milling-Machine, of which the following is a specification.

This invention has reference to improvements in milling machines and its object is 10 to provide a machine which will more thoroughly remove dirt and other substances which should not follow the stock than has heretofore been the case, and carry the removed material to the dust collector for further treatment, and which will cool and 15 partially dry the stock, thereby aiding in the subsequent grinding and bolting to a commensurate extent, this greatly improving the quality of the product and also increasing the yield and profits.

In accordance with the present invention the direction of travel of the stock is broken many times, while the fall of stock from one directing changing means to the next 25 is short, thereby admitting of strong air currents without liability of carrying away any parts of the falling stock except those which it is desirable should be extracted by such air currents. In the present machine the 30 air currents traverse the falling stock during each fall, while the parts are so dimensioned as to prevent any change in the action of the air currents on the dropping stock at different parts of the apparatus, so 35 that there is no liability of uneven action of the air currents and consequent escape of some portions of the removable parts of the stock being carried by said stock beyond the action of the air currents.

The invention will be best understood 40 from a consideration of the following detailed description taken in connection with the accompanying drawings forming a part of this specification, with the understanding 45 that while the drawings illustrate practical forms of the invention it is susceptible of other practical embodiments, wherefore the invention is not confined to any strict conformity to the showing of the drawings 50 but may be changed and modified so long as such changes do not mark any material departure from the salient features of the invention.

In the drawings Figure 1 is an elevation 55 of a machine designed to break stock. Fig. 2 is a section on the line 2—2 of Fig. 1.

Referring to the drawing there is shown a casing 1 through the center of which there extends an air trunk 2 which is assumed to be connected by a pipe 3 with a suction fan, 60 the latter not being shown, but being commonly employed in connection with machines of the character of the present invention. Within the pipe 3 is a cut-off valve 4 which may follow the usual practice. The top of the casing 1 on opposite sides of the air trunk is entered by inlet ducts 5, 6, respectively, while the other or bottom end of the casing is contracted, as indicated at 7, to discharge openings 8, 70 while extending across the discharge portion of the casing is a support 9 crowned by a deflector 10 in the form of an inverted V with its apex substantially central to the air trunk and at approximately the lower end 75 of the latter. Extending from opposite sides of the air trunk are spaced baffles 11 and in alternate relation to these baffles are other baffles 12 extending from the corresponding faces of the casing 1. The baffles 80 all decline at a suitable angle and their interspersed free edges are arranged one below the other in line with the inlets 5 and 6, respectively. Where each baffle 11 joins the air trunk there is an opening or port 13 85 entering the air trunk and where each baffle 12 joins the corresponding face of the casing 1 there is an opening or port 14, the latter being provided with an adjustable cut-off or valve 15 which may be held in adjusted positions by fastening nuts 16 or other suitable devices. Let it be assumed 90 that air is being withdrawn from the trunk 2 through the pipe 3 and consequently air is entering the trunk through all the ports 95 13. Stock is assumed to be entering the casing through the inlets 5 and 6. The stream of stock strikes the uppermost baffles 12 and by them is deflected on to the next succeeding baffles 11 and falls freely 100 between these two baffles in a stream of appropriate size. From the uppermost baffles 11 the stream of stock is directed on to the second set of baffles 12, thence its direction of flow is diverted to the second set of 105 baffles 11 and so on throughout the series of baffles until finally falling from the lowermost baffles 11 the streams find their way to the discharge openings 8 and to a conveyor or other suitable means, whereby the 110 cleaned stock is conveyed to a suitable point of disposal. Underneath each baffle is a

port 13 or 14 as the case may be, the lower-most baffles 11 being coincident with the lower end of the air trunk so that such lower end which is open constitutes inlet 5 ports to the air trunk below such baffles.

It will be noted that the fall from each baffle to the next succeeding baffle is the same throughout the apparatus, while the ports 13 entering the air trunk may be all 10 alike and the ports 14 entering through the walls of the casing may be adjusted as circumstances may require. There are, therefore, streams of air entering the casing underneath each baffle 12 to pass through a 15 stream of stock falling from such baffle on to the next lower baffle and from thence passing to the air trunk through the port 13 underneath the next higher baffle. The 20 baffles are so disposed that the fall of the stream of stock is short, wherefore the air currents may be made much stronger than has heretofore been the custom and much of the material which it is desirable to remove with the light dust is carried into the air 25 trunk without liability of also carrying the heavier material which it is desired should go to the grinding rolls. It is to be observed that the air ports which lead into the air trunk are also located considerably 30 higher than the portions of the streams traversed by the air reaching them, and this is also true of the air inlet ports to the interior of the casing, and even though the heavier particles be constrained to follow 35 the air streams their weight soon overcomes such tendency, whereupon they fall upon the baffles to be directed thereby again into the stream of stock.

It is to be observed that the course of the 40 stream of stock is many times broken in traversing the apparatus and each time the course of the stream of stock is broken it is subjected to an air current of sufficient strength to extract those materials which it 45 is desirable should be removed from the stock, so that should certain materials escape the first air currents they will be acted upon by subsequent air currents until ultimately the stream of stock reaches the outlets 8 in 50 a markedly clean condition. Moreover, the numerous streams of air each independent of the other and traversing its own individual falling stream of stock not only cleanses the stock but cools and dries it, so 55 that it reaches the grinding rolls in such condition as to not only improve the quality of the product, but the yield is increased, and profits are correspondingly increased. In the present apparatus the action of the 60 air currents on the stream of stock is substantially the same throughout the apparatus and at all falls or drops of the stream from one baffle to the other.

The inverted V-shaped deflector at the 65 lower end of the air trunk serves to prevent

filling of the air trunk as might occur were this deflector omitted. The employment of the centralized air trunk with passages for stock on opposite sides thereof greatly increases the capacity of the machine without materially increasing the cost of operation. 70

It is advantageous to employ strong air streams, since the cleansing is much more effective than where the air streams are of less force, but in devices as heretofore constructed for like purposes no attempt has been made to practically unify the air streams so far as their effect is concerned, and to distribute these air streams throughout substantially the whole range of movement of the stock through the apparatus. 75 80

What is claimed is:—

1. In a machine for the purpose described, a casing contracted at the lower end and there provided with a discharge opening, an exhaust air trunk rising from the lower end of the casing and having its lower end spaced above and open to the discharge opening of the casing, a series of superposed declining baffles on and exterior to the air trunk, and the latter having an equal number of freely open air ports each in underlying relation to the upper end of a respective baffle, and another series of declining baffles extending from an inner wall of the casing in opposition to and alternation with the first-named baffles, and the said inner wall of the casing being provided with as many air ports as there are baffles thereon, each air port being associated with and individual to a respective one of the second-named baffles and in underlying relation to the upper end thereof, the associated series of baffles discharging into the same discharge opening to which the exhaust air 95 100 trunk opens at its lower end. 105

2. In a machine for the purpose described, a casing contracted at the lower end into discharge openings, a centralized exhaust trunk rising from the lower end of the casing with its inlet above and open to the discharge openings, a series of superposed declining baffles exterior to and on opposite sides of the air trunk and the latter being provided with an equal number of 110 freely open air ports each in underlying relation to the upper end of a respective baffle, and other series of declining baffles on the opposite inner walls of the casing in opposition to and alternation with the first-named baffles, and the casing being provided with air ports equal in number to the second-named series of baffles with each air port individual to a respective baffle in underlying relation to the upper end thereof, the associated series of baffles on opposite sides of the air trunk discharging into the respective discharge openings to which the air trunk 115 120 125 is common.

3. In a machine for the purpose described, 130

a casing contracted at the lower end into discharge openings, a centralized exhaust trunk rising from the lower end of the casing with its inlet above and open to the discharge openings, a series of superposed declining baffles exterior to and on opposite sides of the air trunk and the latter being provided with an equal number of freely open air ports each in underlying relation to the upper end of a respective baffle, and other series of declining baffles on the opposite inner walls of the casing in opposition to and alternation with the first-named baffles, and the casing being provided with air ports equal in number to the second-named series of baffles with each air port individual to a respective baffle in underlying relation to the upper end thereof, the associated series of baffles on opposite sides of the air trunk discharging into the respective discharge openings to which the air trunk is common, and each of the second-named series of air ports through the outer walls of the casing being provided with a controllable means for regulating its effective area.

4. In a machine for the purpose described, a suitable casing, a centrally located air trunk therein extending from the top of the casing to a point adjacent the bottom thereof, said air trunk carrying on each side series of baffles declining from the air trunk toward the corresponding wall of the casing and said air trunk being provided with an air port associated with each baffle and in underlying relation thereto at the junction of the baffle with the air trunk, other series of declining baffles extending from corresponding walls of the casing in alternation with and in opposite direction to the first named baffles, the casing walls being provided with air ports each in underriding relation to the upper end of a corresponding

baffle where joining the casing wall, and inlets for stock on opposite sides of the air trunk and in line with the free edges of the corresponding series of baffles, the casing also being provided with an inverted V-shaped deflector in underriding centralized relation to the lower end of the air trunk.

5. In a machine for the purpose described, a suitable casing, a centrally located air trunk therein extending from the top of the casing to a point adjacent the bottom thereof, said air trunk carrying on each side a series of baffles declining from the air trunk toward the corresponding wall of the casing and said air trunk being provided with an air port associated with each baffle and in underlying relation thereto at the junction of the baffle with the air trunk, other series of declining baffles extending from corresponding walls of the casing in alternation with and in opposite direction to the first named baffles, the casing walls being provided with air ports each in underriding relation to the upper end of a corresponding baffle where joining the casing wall, and inlets for stock on opposite sides of the air trunk and in line with the free edges of the corresponding series of baffles, the casing also being provided with an inverted V-shaped deflector in underriding centralized relation to the lower end of the air trunk.

In testimony, that I claim the foregoing as my own, I have hereto affixed my signature in the presence of two witnesses.

WILLIAM R. LAKEY.
